UNITED STATES PATENT OFFICE.

WILLIAM HAYES, OF PAWTUCKET, RHODE ISLAND.

STRAINER.

SPECIFICATION forming part of Letters Patent No. 634,455, dated October 10, 1899.

Application filed February 24, 1899. Serial No. 706,683. (No model.)

To all whom it may concern:

Be it known that I, WILLIAM HAYES, a citizen of the United States of America, and a resident of Pawtucket, county of Providence, 5 and State of Rhode Island, have invented certain new and useful Improvements in Strainers, of which the following is a specification.

My invention relates to improvements in strainers in which the receptacle which holds 10 the liquid is separable from the base of the strainer and fits the latter in such a way as to admit of the introduction of a suitable straining fabric or substance; and the object of my invention is to provide a strainer in which the 15 various parts are separable in order to facilitate the cleansing thereof and in order to permit of the introduction of a variety of straining or filtering fabrics or substances. I accomplish these objects by the mechanism 20 shown in the accompanying drawings, in which—

Figure 1 shows the lower portion and delivery-tube of my device; Fig. 2, the liquid-receptacle, and Figs. 3 and 4 the two together 25 in section.

The same parts are designated by the same letters throughout the several views.

In Fig. 1, A is a shallow box-like receptacle having the delivery-tube c projecting 30 downwardly therefrom, the upper end of c being provided with the gauze or netting b. This member of my invention may be made of any suitable material, but preferably of sheet metal, such as copper or tin. The member 35 B, Fig. 2, is a deeper box-like receptacle, made also preferably of sheet metal and of such a size as to fit easily into the member A. The bottom of B is also provided with a metallic netting or gauze a. In Fig. 3 the member B is seen in position for use fitted to the member A. Between the two members is a filtering fabric or pad C, which may be of cotton flannel or one or more thicknesses of suitable cloth or paper or other proper filtering 40 material. The pad C is placed in the bottom of A, and the member B fits tightly down upon it, holding it in place, the pad serving as a packing to prevent leakage. The liquid to be strained is poured into the receptacle B 45 and finds its way through the netting a and the filtering-pad C into the delivery-tube c.

Instead of using the filtering-pad C fitted to

the receptacle A a piece of muslin cloth of any size whatever may be placed over A, the superfluous margin of the cloth hanging down 55 upon the outside. The member B is then inserted into A, inclosing the muslin tightly between the mesh a and the bottom of A, and the straining then proceeds as before, the parts being easily separated for the purpose 60 of changing the cloth to a new portion thereof or for the purpose of cleaning the same.

It is not necessary that B should have the network or mesh a at the bottom of it, as it will work without the same. It will also be 65 apparent that the shape of my device is immaterial, the square shape being made simply for convenience. It may be made in a circular form or in any other suitable shape. The delivery-tube c may also be of any re- 70 quired shape or size.

The advantages of my device are that in the straining of liquids every part of my strainer is quickly accessible for the purpose of cleansing, that a large body of liquid may 75 be set to strain, the quantity depending solely upon the size of the receptacle B without any attention on the part of the person using the strainer, that the part B being separable from A permits the use of a variety of filtering materials or fabrics being used whether in the form of a pad, as shown at C in Fig. 3, or of muslin, cotton flannel, or other cloth, as shown at C', Fig. 4, and of course instead of cloth paper or any other fabric may be sub- 85 stituted.

Having now described my invention, what I claim, and desire to secure by Letters Patent, is—

A strainer composed of a lower member A 90 with raised edges and having a delivery-tube c projecting downwardly therefrom; a separable upper member B fitting into said lower member; and a pad of filtering material held in position by the engagement of A and B, 95 substantially as described for the purpose specified.

Signed by me at Pawtucket, Rhode Island, this 22d day of February, A. D. 1899.

WILLIAM HAYES.
